STARTING MEANS FOR COLD ELECTRODE
VACUUM TUBE DEVICES

Albert M. Skellett, Madison, and Bernard G. Firth, Newark, N.J., assignors to Tung-Sol Electric Inc., a corporation of Delaware

Filed Nov. 21, 1957, Ser. No. 697,928

9 Claims. (Cl. 315—12)

The present invention relates to cold electrode vacuum tube devices of the type wherein the current carriers are electrons emitted from an oxide coating on one electrode and collected by one or more electrodes maintained at a positive potential with respect to the coated electrode. In such type of device the oxide coating, which may be magnesium oxide, is relatively porous and for most efficient emission of electrons comprises a uniform distribution of microscopic sponge-like structures. Once initiated, the emission of electrons from the coating is copious and self-sustaining. Various starting means for such devices have been utilized such as a spark coil or a source of ultra violet light or a directly or indirectly heated cathode within the envelope for thermally generating primary electrons for bombardment of the coated electrode. Such known starting means are either impractical for commercial devices or require too long a time to bring the tube to full operating current conditions. The present invention comprises novel means for starting conduction in cold cathode vacuum tubes that does not have the disadvantages inherent in starting means heretofore employed.

The novel starting means of the invention operates by field emission and comprises an additional electrode provided with a fine point directed toward the coated electrode or cathode and maintained during starting at a relatively high negative potential with respect to the coated electrode. The tip of the pointed electrode may be located between the coated cathode and the collector electrode or on the side of the collector electrode remote from the cathode.

For a better understanding of the invention and of specific embodiments thereof, reference may be had to the accompanying drawing of which:

Fig. 1 is a perspective view, partly cut away, of a cold cathode vacuum tube provided with a starting electrode embodying the invention;

Fig. 2 is a diagrammatic horizontal section view taken on the line 2—2 of Fig. 1;

Fig. 3 is a diagrammatic partial vertical sectional view through a tube like that of Fig. 1 but illustrating a different location within the envelope of the starting electrode;

Fig. 4 is a horizontal sectional view taken on the line 4—4 of Fig. 3;

Fig. 5 is a diagrammatic horizontal sectional view similar to Figs. 2 and 4 but showing two starting electrodes; and

Fig. 6 is a view of the point of the starter electrode on a greatly magnified scale.

The cold cathode vacuum tube illustrated in Figs. 1 and 2 comprises an outer envelope 2 of glass sealed to a button type glass base 4. Mounted on the base 4 as by means of support rods 6 is a cylindrical metal shield 8 which encompasses a collector grid or anode 10 of wire mesh which in turn surrounds the cylindrical cold cathode 12. The cathode 12 is preferably of nickel and carries a coating 14 of magnesium oxide which is porous

2

and, as heretofore indicated, in sponge-like form of microscopic structures. The coating may be applied by spraying, by vacuum evaporation, or by the magnesium burning technique described in U.S. Patent to Dobiscek et al. No. 2,802,127. The particular method of forming a coating having the proper physical structure and thickness (of the order of 28 to 48 microns) forms no part of the present invention. The shield 8, collector electrode 10 and cathode 12 are supported between spaced mica wafers 16. Support leads 18 and 20 for the respective electrodes 10 and 12 are sealed through the base 4 and connected to pin terminals 22 and 24 respectively. One support post 6 for the shield 8 is also sealed through the base and connected to a pin terminal 25. The shield 8 is provided with an opening 26 substantially mid way of its length and through this opening extends the pointed end of a wire electrode 28, the point 29 of the electrode being directed toward the cathode 12. The electrode 28 is supported by a rod 30 which is fused through the base 4 and connected with a fourth pin terminal 32. The electrode 28 may be made of any conductive, refractory and preferably rather oxidation resistant material of fairly high tensile strength such as tungsten, stainless steel, iridium, etc. The point 29 thereof is etched down to a radius of curvature of about half a micron or less. The point is so oriented with respect to the openings of grid electrode 10 that there is an unobstructed path from the point to the cathode coating for travel of electrons given off by field emission from the point when a high negative potential with respect to the cathode is impressed upon terminal 32. A fine tip or point on tungsten wire may be formed quickly and effectively by an anodic process in potassium hydroxide solution (0.5 gram potassium hydroxide for each cc. of water) with one or two crystals of cupric nitrate and a copper cathode under carefully controlled conditions of current and voltage. For example, the tip of a .005" diameter tungsten wire is immersed $\frac{1}{16}$ " to $\frac{1}{8}$ " in such solution and the applied voltage kept constant at precisely 1 volt. The current will fall from about 10 milliamperes to $2\frac{1}{2}$ milliamperes and then start to suddenly drop off. At the start of this second current drop the circuit is quickly opened to prevent etching off the formed point. A fine tungsten point is thus formed which after washing carefully and drying is ready to be mounted in the tube.

In Fig. 1 a circuit for starting and operating a tube of the above described construction is diagrammatically indicated as comprising a source 34 of direct current voltage, the negative terminal of which is connected to pin terminal 24 and the positive terminal of which is connected through an adjustable resistor 36 and half of switch 38 to terminal 22 and a second source 40 of direct current potential the positive terminal of which is connected to terminal 24 and the negative terminal of which is connected through a resistor 42 and the other half of switch 38 to terminal 32. Source 34 may be of the order of 400 volts and source 40 of 1000 volts or more. Resistor 42 is of large resistance, of the order of 100-1000 megohms, whereas resistor 36 is of relatively low resistance of the order of 5 to 50 kilohms. The circuit connection for the shield 8 is to the cathode 12 as the function of the shield is solely to protect the cathode from glass wall charges of the envelope resulting from electron bombardment. Such charging of the glass walls renders the tube unstable and electrically noisy.

With the above described construction of cold cathode vacuum tube and a circuit of the above type, when switch 38 is closed starting can be effected rapidly at a current of less than .01 microampere through resistor 42. The starting time depends upon the voltage applied

to the starting electrode and may vary from less than one-half second for an applied voltage of about 1200 volts to one or two seconds for an applied voltage of 800 volts. Once started, the tube will pass a current in the order of milliamperes per sq. cm. of cathode surface between the cathode 12 and electrode 10 which can be cut off and re-initiated merely by opening and closing the switch 38. The high potential gradient at the point 29 produced by the relatively high potential between it and the other electrodes is such that electrons are given off by field emission from the point and these electrons strike the magnesium oxide coating causing emission of secondary electrons which in turn are drawn to the grid electrode, thus initiating the self-sustaining electron emission from the cathode. The cathode remains cold but glows a bluish color during conduction in the tube. Once the tube is started the voltage may be removed from the starting electrode or left applied as desired.

Starting of a tube such as that described may be similarly effected at a lower negative starting potential when the point of a starting electrode is closer to the cathode, for example between electrodes 10 and 12. Such a construction is shown diagrammatically in Figs. 3 and 4 wherein the various parts of the tube are given the same reference numerals as are applied in Figs. 1 and 2. In the construction illustrated in Figs. 3 and 4 the conductive support 30 for the starting electrode 28 is positioned between the shield 8 and grid electrode 10 and the electrode 28 extends through an opening in the grid 10 so as to bring the pointed tip of the electrode between the grid and the coated cathode 12. When the starting electrode is positioned as shown in Figs. 3 and 4 a small dark spot may or may not appear on the luminous cathode at a location aligned with the point of the starting electrode. This dark spot may be due to an electrostatic field created by the presence of the points or it may be due to slight contamination of the coating by the point during tube processing. So long as the spot remains relatively small it does not seriously interfere with the operation of the tube. With this arrangement it has been observed that a negative potential of 600 volts with respect to the cathode will start conduction in the same time as the negative potential of 1000 volts applied to the starter when positioned as in Figs. 1 and 2.

Even more rapid starting may be effected when one or more additional point starting electrodes are provided directed toward different areas of the cathode coating. Fig. 5 illustrates such an arrangement where pointed starting electrodes 28a and 28b are directed toward diametrically disposed areas of the cathode coating. Electrodes 28a and 28b should be mounted on separate conductive supports and connected through separate resistors and the switch to one common E.M.F. supply.

The invention has now been described with reference to various embodiments thereof. Obviously various changes in the particular construction of tubes could be made without departing from the spirit of the invention or the scope of the accompanying claims. For example, although cylindrical electrodes have been described and illustrated, electrodes of other cross sectional shape, such as semi-cylindrical, oval or flat could be employed. Similarly, the protective shield could be omitted if desired (though this is not recommended) and various locations of the starting electrode, in addition to those suggested, will occur to those skilled in the art.

The following is claimed:

1. A cold cathode vacuum tube comprising an evacuated envelope, a cathode therein comprising a metallic member having a surface coating thereon of the type adapted to emit a copious self-sustaining stream of electrons once electron emission is initiated, a collector electrode for electrons emitted from the cathode and a start-

er electrode comprising a metallic member having a fine pointed tip directed toward the cathode and adapted to emit primary electrons by field emission when a high negative potential with respect to the cathode is impressed thereon.

2. A cold cathode vacuum tube according to claim 1 wherein said collector electrode has openings therein of which one is aligned with the tip of said starter electrode to permit passage of primary electrons therethrough.

3. A cold cathode vacuum tube according to claim 2 including a metallic shield within said envelope having an aperture therein aligned with said one opening in said collector electrode, said collector electrode being positioned between said cathode and said shield and said starter electrode extending through said aperture.

4. A cold cathode vacuum tube according to claim 1 wherein said collector electrode has openings therein and said starter electrode extends through one of said openings.

5. A cold cathode vacuum tube according to claim 1 wherein the radius of curvature of the pointed tip of said starter electrode is of the order of one-half micron.

6. The cold cathode vacuum tube according to claim 1 including a second starter electrode having a fine pointed tip directed toward another portion of said coated electrode and adapted, when a voltage negative with respect to said coated electrode is impressed thereon to emit primary electrons by field emission.

7. The cold cathode vacuum tube according to claim 1 wherein said cathode is generally cylindrical and coated over the external surface thereof, said collector electrode surrounds said cathode and has openings therein, said starter electrode extending through one of said openings.

8. The cold cathode tube according to claim 1 wherein said cathode is generally cylindrical and coated over the external surface thereof, said collector electrode surrounds said cathode and has openings therein, the tip of said starter electrode being aligned with one of the openings in said collector electrode.

9. A cold cathode vacuum tube and energizing means therefor comprising a vitreous envelope and a base hermetically sealed thereto, a metallic sheet-like electrode within said envelope and mounted on said base, said electrode having a magnesium oxide porous coating thereon composed of minute sponge-like structures, an openwork collector electrode within said envelope and mounted on said base in spaced relation to said sheet-like electrode, a starting electrode within said envelope comprising a wire of refractory conductive material having a fine pointed tip at one end thereof, conductive means for supporting said starting electrode from said base with the pointed tip thereof directed toward the coating on said sheet-like electrode, means for impressing a potential difference across said sheet-like electrode and said collector electrode with the collector electrode at a positive potential with respect to said sheet-like electrode and means for impressing a higher potential difference across said sheet-like electrode and said starting electrode with said sheet-like electrode at a higher potential than said starting electrode whereby primary electrons emitted from the pointed tip of said starting electrode by field emission strike said coating and cause self-sustaining emission of electrons from said coating which are drawn to said collector electrode.

10. The cold cathode tube according to claim 9 wherein the collector electrode is a metallic sheet-like electrode having a magnesium oxide porous coating thereon composed of minute sponge-like structures, the starting electrode is a wire of refractory conductive material having a fine pointed tip at one end thereof, conductive means for supporting said starting electrode from said base with the pointed tip thereof directed toward the coating on said sheet-like electrode, means for impressing a potential difference across said sheet-like electrode and said collector electrode with the collector electrode at a positive potential with respect to said sheet-like electrode and means for impressing a higher potential difference across said sheet-like electrode and said starting electrode with said sheet-like electrode at a higher potential than said starting electrode whereby primary electrons emitted from the pointed tip of said starting electrode by field emission strike said coating and cause self-sustaining emission of electrons from said coating which are drawn to said collector electrode.
